UNITED STATES PATENT OFFICE.

CARL RADITSCH, OF CAMDEN, NEW JERSEY.

NECKBAND FORMER AND STRETCHER.

Application filed June 30, 1927. Serial No. 202,686.

My invention comprehends a novel neck band former and stretcher which is designed to be employed in the ironing of shirts, and which can be adjusted by the operator to fit neck bands of different sizes.

It further comprehends a novel neck band former wherein the body portion of the device has a rotatable member provided with a helical rib which is operatively connected 10 with expandable bands to effect their expansion or contraction.

Other novel features of construction and advantage will hereinafter more clearly appear in the detailed description and the appended claims.

For the purpose of illustrating the invention, I have shown in the accompanying drawing a typical embodiment of it, which, in practice, will give reliable and satisfactory 20 results. It is, however, to be understood that this embodiment is typical only and that the various instrumentalities of which my invention consists can be variously arranged and organized, and the invention is not, therefore, limited to the precise arrangement and organization of these instrumentalities as herein set forth.

Figure 1 is a top plan view of a neck band former and stretcher, embodying my invention.

Figure 2 is a section on line 2—2 of Figure 3.

Figure 3 is a section on line 3—3 of Figure 2.

Figure 4 is a side elevation of a bar with a band shown in section.

Figure 5 is a section on line 5—5 of Figure 1.

Similar numerals of reference indicate corresponding parts.

Referring to the drawings:

1 designates the body portion of a neck band former and stretcher embodying my invention and consisting of sections 2 and 3 which are secured together by fastening devices 4.

The bottom section 3 is recessed as at 5 to receive a rotatable member 6 having a raised helical rib 7. The member 6 is actuated by means of a key 8 having a polygonal portion 9 which fits a correspondingly shaped recess 10 in the member 6. The key is secured in place by a nut 11, the bottom section 3 being recessed to receive said nut. The key has a handle 12 pivoted to it, and the upper section 2 is recessed as at 13 to receive said

key. The outer portion of the key is preferably provided with a shoulder 14 as shown in Figure 3.

15 designates a band which partly surrounds the body portion and is secured thereto by means of fastening devices 16. The band 15 near its free ends has fixed to it the headed keys 17 which extend into the keyways or slots 18 in the movable bands 19 and 20 each of which at their rear ends is bent or clipped over as at 21, the juxtaposed portion of the band, see more particularly Figure 5. The forward portions of the band 19 and 20 terminate in lateral extensions 65 which conform substantially to the contour of the juxtaposed portions of the body portion or casing 1. The extensions have fixed to them bars 22 which are guided in the slots 23 in the sections 2 and 3. These bars have a series of laterally extending curved slots 24 to receive the helical rib 7 of the member 6.

The operation will now be apparent to those skilled in this art and is as follows:—

By turning the key 8, the actuating member will turn thereby causing the bands 15, 19 and 20 to be expanded or contracted so that the bands will fit neck bands of various sizes, for example any size from fourteen inches to eighteen and a half inches. The helical rib 17 causes the bars 22 to move outwardly or inwardly depending upon the direction in which the key 8 is turned.

The casing or body portion 1 is preferably made from aluminum or aluminum alloy or other light metal, and the bands are preferably made of spring metal.

Special attention is directed to the fact, that, when the actuating member 6 is adjusted, the helical rib 7 not only serves to effect the expansion and contraction of the bands but also retains such bands in the position to which they have been adjusted. The casing has in general a heart shaped contour.

It will be apparent that as the bars 22 are moved outwardly or inwardly, the expansion or contraction of the bands 15, 19 and 20 is effected. The slideable bands 19 and 20 have a pin and slot connection with the fixed band 15, so that the desired extension or retraction of the bands 19 and 20 will be effected as well as the expansion or contraction of the composite bands formed by the bands 15, 19 and 20.

Special attention is directed to the heli-

cal rib 7 and its co-operation with the bands 22, which latter are slotted to conform to the portions of the helical rib 7 which co-operate with the walls of such slots.

5 It will now be apparent that I have devised a new and useful neck band former and stretcher which embodies the features of advantage enumerated as desirable in the statement of the invention and the above 10 description, and that while I have, in the present instance, shown and described a preferred embodiment thereof which will give in practice satisfactory and reliable results, it is to be understood that this embodiment 15 is susceptible of modification in various particulars without departing from the spirit or scope of the invention or sacrificing any of its advantages.

Having thus described my invention what 20 I claim as new and desire to secure by Letters Patent, is:

1. A neck band former and stretcher, comprising a body portion, an expandible and contractible band surrounding said body portion and carried by it, and a manually con-

trolled actuating member rotatably carried by said body portion and having a helical member operatively connected with said band to effect its expansion and contraction.

2. A neck band former and stretcher, 30 comprising a sectional casing, an expandible and contractible sectional band fixed to one side of the casing and having free ends at the opposite side of the casing, bars guided in the casing and fixed to said band, and a 35 member rotatably mounted in said casing and provided with a helical rib co-operating with said bars to effect the expansion and contraction of said band.

3. A neck band former and stretcher, 40 comprising a casing, a sectional band having one section fixed to the casing, and having sections slidably carried by said fixed sections and having their free ends laterally disposed, slotted bars fixed to said slidably disposed, a member rotatably mounted in said casing and having a helical rib which is received in slots of said bars, and means to actuate said member.

CARL RADITSCH.
